EXCHANGEABLE HEEL

Filed March 25, 1931

Inventor:

Erich Grauert
Erich Grauert

UNITED STATES PATENT OFFICE

ERICH GRAUERT, OF HALBERSTADT, GERMANY

EXCHANGEABLE HEEL

Application filed March 25, 1931, Serial No. 525,176, and in Germany March 26, 1930.

This invention relates to an exchangeable heel which, as compared with other heels of this type, can be detached from the shoe without it being first necessary to loosen a screw, nut or wedge on the heel. The heel according to the invention is slipped on to a plate fixed on the shoe, a knob secured to a spring engaging in a depression in a plate, fixed on the heel, so that the heel is securely held on the shoe. If it is desired to remove the heel from the shoe, it is sufficient to exert a strong jerk or pull on the shoe so that the knob disengages from the heel plate and the heel drops off from the shoe.

A heel according to the invention is illustrated by way of example in the accompanying drawing in which:

Fig. 1 is a longitudinal section through the heel portion of the shoe.

Fig. 2 is a bottom plan view of the plate fixed on the shoe.

Fig. 3 is a top plan view of the plate fixed on the heel.

Fig. 4 is a longitudinal section on line 4-4 of Fig. 2.

Fig. 5 is a longitudinal section on line 5-5 of Fig. 3.

Fig. 6 is a cross section on line 6-6 of Fig. 2.

Fig. 7 is a cross section on line 7-7 of Fig. 3.

A metal plate *a* corresponding to the shape of the heel is fixed on the heel portion of the shoe and provided with three parallel dove-tailed grooves *b* and *c*, the groove *b* being arranged on the outer edge of the plate *a*, whereas the groove *c* is in the middle of the plate towards its rear end. The groove *c* extends into an elongated wide recess *d*, reaching almost to the front edge of the plate. A blade spring *e* is accommodated in this recess and carries on its free end a round knob *f*.

A metal plate *h* corresponding to the shape of the heel is fixed on the heel *g* (Fig. 1) and has dove-tailed projections *b'* and *c'*, corresponding to the grooves *b* and *c*. A round depression *f'* is also formed in the plate *h*

at a point corresponding to the position of the knob *f* of the spring *e*.

In order to slip the heel on the plate *a*, the plate *h* is connected to the plate *a* so that the projection *c'* engages in the recess *d* behind the spring *e*, after which the three projections *b'* and *c'* can easily be slipped into the grooves *b* and *c*. The distance which the heel is shifted, therefore only corresponds to the length of the projections *b'*, *c'* so that the heel can easily be slipped on to the plate *a* from the shank side, even under difficult circumstances. The knob *f* engaging in the depression *f'* holds the heel rigidly on the shoe so that it is impossible for the heel to automatically become detached from the shoe. In order to effect the removal, a suitably strong pull in the direction of the arrow shown in Fig. 1 is necessary, which pull must be sufficiently strong to pull the knob out of the depression *f'* so that the heel is detached from the shoe.

In this connection it is thought of accidents which often occur owing to a railway official or some other person getting his foot jammed between points so that he is run over by a train, because he is unable to remove his foot in time as the heel is jammed in the points. If the heel according to the invention is employed, such accidents cannot occur, as, if the person, whose heel is jammed in the points, exerts a strong pull on the heel, he frees the shoe. The heel according to the invention possesses the further advantage that it is not apparent that the heel is removable, as the holding device does not project from the heel. The heel is also suitable for ladies' shoes.

I claim:

A detachable heel comprising in combination with a heel stump on the shoe, a metal plate corresponding to the shape of and fixed on said heel stump having in its lower side two short dove-tailed grooves extending from its front face one near each corner and a short dove-tailed groove in the middle near its rear end, a recess extending from said middle groove to near the front face of the plate, a spring in the recess fixed at its front end to said plate, a downwardly projecting

hemispherical knob near the free end of said spring, a detachable second metal plate also corresponding to the shape of the heel stump having a hemispherical depression in its middle, and short dove-tailed projections on the
5 upper side of said detachable plate registering with and corresponding in shape to the dove-tailed grooves in said fixed plate adapted to slide in said grooves to connect said detachable plate to said fixed plate, said knob
10 adapted to engage in the depression in said detachable plate to lock said detachable plate on said fixed plate but to be disengaged from said depression upon sudden pressure being exerted on the rear end of the heel to allow
15 said detachable plate to be slipped off said fixed plate.

In testimony whereof I affix my signatore.
ERICH GRAUERT.
